UNITED STATES PATENT OFFICE.

WILLIAM F. RUSCHE, OF MILWAUKEE, WISCONSIN.

DESIGN FOR A LAMP SHADE.

Application filed July 3, 1922. Serial No. 2,936. Term of patent 3½ years.

To all whom it may concern:

Be it known that I, WILLIAM F. RUSCHE, a citizen of the United States, residing at Milwaukee, in the county of Milwaukee and State of Wisconsin, have invented a new, original, and ornamental Design for Lamp Shades, of which the following is a specification, reference being had to the accompanying drawing, forming part thereof.

I claim:

The ornamental design for a lamp shade, as shown.

WILLIAM F. RUSCHE.
